UNITED STATES PATENT OFFICE.

GEORGE A. KING, OF MAPLE FALLS, WASHINGTON.

DRIVING MECHANISM.

1,221,334.

Specification of Letters Patent. Patented Apr. 3, 1917.

Application filed November 16, 1915. Serial No. 61,810.

To all whom it may concern:

Be it known that I, GEORGE A. KING, a citizen of the United States, residing at Maple Falls, in the county of Whatcom and 5 State of Washington, have invented certain new and useful Improvements in Driving Mechanism; and I do hereby declare the following to be a full, clear, and exact description of the invention, such as will enable 10 others skilled in the art to which it appertains to make and use the same.

My invention relates to new and useful improvements in propelling and guiding means for vehicles and primarily for use in 15 connection with a vehicle adapted to carry breaking or other forms of plows, and my prime object is to provide means for turning the vehicle in a very small radius.

A further object is to provide means for 20 applying the power in such manner as to propel the vehicle forwardly or rearwardly.

A further object is to provide means for rotating the forward axle to guide the vehicle.

25 And a further object is to provide means for applying power to both axles of the vehicle simultaneously or to the forward axle singly.

Other objects and advantages will be 30 hereinafter set forth and more particularly pointed out in the accompanying specification.

In the accompanying drawings which are made a part of this application.

35 Figure 1 is a detail sectional view as seen on line 1—1 of Fig. 2.

Fig. 2 is a sectional view as seen on line 2—2 of Fig. 1, and

40 Fig. 3 is a detail top plan view of the propelling and guiding mechanism.

Referring to the drawings in which similar reference numerals designate corresponding parts throughout the several views, 1 and 2 indicate the front and rear 45 supporting wheels respectively for the vehicle which are mounted upon axles 3 and 4 respectively, each axle being preferably surrounded by a tubular casing 5 and 6, the casing 5 being provided with an upwardly extending yoke 7, while the casing 6 is provided with a horizontally extending yoke 8.

50 Connected to the yoke 8 at its longitudinal center is a sleeve 9 through which extends a shaft 10, the rear end of the shaft having a gear 11 which meshes with a similar gear 12 on the rear axle 4, while to the forward

end of the shaft 10 is movably secured a gear 13 which meshes with a similar gear 14 carried by a vertically extending shaft 15.

Mounted upon an elongated collar 16 surrounding the inner end of the shaft 10 is a platform 17 which is adapted to form a support for any suitable form of combustion engine (not shown) and also for the driver, a gear 18 being mounted upon a shaft 19 to receive the power from the motor, the ends of the shaft 19 being rotatably mounted in a yoke 20.

The shaft 19 has attached thereto a gear 24 which meshes with an elongated pinion 25 carried by a shaft 26, said shaft being adjustably mounted in the upper ends of the yoke 20, said yoke being supported by an arm 27 extending from the sleeve 28 surrounding the shaft 15, and in view of the elongated pinion 25, the shaft may be moved a suitable distance longitudinally in either direction without being disengaged from the gear 24.

The shaft 26 has attached thereto beveled gears 29 and 30 which are adapted to mesh with the opposite edges of a bevel gear 31 carried by a horizontally extending shaft 32, said gears being employed for driving the wheels of the vehicle forwardly or rearwardly.

The shaft 26 is moved longitudinally to bring either of the gears 29 or 30 into mesh with the gear 31 by pivoting a lever 33 to the yoke 20, one end of the lever engaging between collars 34 on the shaft 26 which will permit said shaft to rotate but cause the shaft to move longitudinally when the lever is rocked on its pivot, the opposite end of the lever having a latch 35 which cooperates with the rack 36 for holding the lever in adjusted position and by forming a plurality of notches in the rack, both of the gears 29 and 30 may be locked out of engagement with the gear 31, thus stopping the propulsion of the vehicle, although the engine may still remain running.

The shaft 32 extends forwardly from the gear 31 and has a bevel gear 37 fixed thereto which meshes with a similar gear 38 attached to the upper end of the shaft 15 thereby imparting rotating movement to the rear axle 4 so long as the gear 13 is in mesh with the gear 14, but when it is desired to disconnect the driving power from the rear axle, the lever 39 is thrown forwardly thereby sliding the gear 13 rearwardly on the

shaft 10 and disconnecting the same from the gear 14, a suitable rack 40 and latch 41 being provided for holding the lever 39 in its adjusted position.

The forward end of the shaft 32 has a pinion 42 fixed thereto which meshes with the pinion 43 fixed to the upper end of a shaft 44, said shaft extending through a tubular casing 45 carried by the yoke 7, the lower 10 end of the shaft 44 having a pinion 46 attached thereto which meshes with the pinion 47 fixed to the front axle 3, thus imparting rotating movement to said axle when the gear 31 is rotated.

Attached to the connecting bar of the yoke 7 is a circular rack 48 with which meshes a gear 49 carried by a shaft 50, said shaft finding a bearing in the extension 51 of the casing 53 carrying the shaft 32.

Fixed to the upper end of the shaft 50 is a bevel gear 53' with which meshes a bevel pinion 54 attached to one end of a steering shaft 55, the opposite end of the steering shaft having a steering wheel 56 which may 20 be readily grasped to operate the steering mechanism.

When the vehicle is traveling forwardly the power is preferably applied between the front and rear axles by connecting the gear 30 with the gear 14 and the gear 29 with the gear 31, but when the end of the field is reached and it is desired to make a short or abrupt turn, the lever 39 is operated to disengage the gear 13 from the gear 14, thereby disconnecting the power from the rear axle 4 and by operating the hand wheel 56 to throw the forward wheels in position at right angles to the rear wheels or to a greater extent if desired, the vehicle may be 30 turned from end to end in a very limited space, thus rendering the device particularly applicable for use in a small plot of ground, although it will be clearly understood that it can be used equally as well in a larger plot 40 of ground. If it is desired to move the vehicle rearwardly, the latch 35 is disengaged from the rack 36 and the free end of the lever 33 thrown inwardly its full distance which will move the gear 30 into engagement with the gear 31, thereby reversing the rotation of the axles 3 and 4 and causing the vehicle to travel rearwardly.

When it is desired to stop the movement of the vehicle in either direction without 50 stopping the operation of the engine, the lever 33 may be swung on its pivot to a point substantially midway between its extreme movement which will disengage both of the gears 29 and 30 from the gear 31, thus disconnecting the motor from the driving gears of the vehicle and permitting the vehicle to stand idle while the motor is still rotating.

It will likewise be seen that by connecting the various casings together by couplings, as 60 shown, a very rigid frame construction will

be provided and by attaching the platform to the sleeve 16 which is rotatable on the shaft 10 the wheels of the vehicle may pass over objects without affecting the position of the motor with respect to the gear 18.

Having thus fully described my invention what I claim as new and desire to secure by Letters Patent of the United States, is:—

1. A vehicle of the class described, comprising the combination with a pair of axles, wheels connected thereto and gears connected to said axles, of a plurality of shafts interposed between said axles, coöperating gears carried by said shafts to impart motion to the gears of the axles, an adjustable shaft, a pair of spaced bevel gears carried by said shaft, a bevel gear carried by one of the connecting shafts, means to move the adjustable shaft to engage either of the gears carried thereby with the gear of the connecting shaft, an elongated pinion on said adjustable shaft, and means to impart power from a motor to said elongated pinion.

2. A vehicle of the class described comprising the combination with a front and rear axle, supporting wheels on said axle and gears fixed to said axle, of a plurality of vertically and horizontally disposed shafts extending from the front to the rear axle, a plurality of beveled cogs at the meeting ends of said shafts and meshing with each other, means to engage or disengage one set of said beveled cogs whereby power will be connected to or disconnected from the rear axle, means to apply power to said connecting shafts to drive the supporting wheels, and additional means for reversing the movement of said wheels or disconnecting the driving power from the connecting shaft.

3. A vehicle of the class described, comprising the combination with a pair of axles, wheels connected thereto and gears connected to said axles, of a plurality of shafts interposed between said axles, coöperating gears carried by said shafts to impart motion to the gears of the axles, an adjustable shaft, a pair of spaced bevel gears carried by said shaft, a bevel gear carried by one of the connecting shafts, a ratchet lever to move the adjustable shaft to engage either of the gears carried thereby with the gear of the connecting shaft, an elongated pinion on said adjustable shaft and means to impart power from a motor to said elongated pinion.

4. A vehicle of the class described, comprising the combination with a front and rear axle, supporting wheels on said axle and gears fixed to said axle, of a plurality of vertically and horizontally disposed shafts extending from the front to the rear axle, a plurality of beveled cogs at the meeting ends of said shafts and meshing with each other, a ratchet lever to move one set of said beveled cogs into and out of engagement whereby power will be connected to or disconnected

from the rear axle, means to apply power to said connecting shafts to drive the supporting wheels, and additional means for reversing the movement of said wheels or disconnecting the driving power from the connecting shaft.

In testimony whereof I have signed my

name to this specification in the presence of two subscribing witnesses.

GEORGE A. KING.
